US0D1053487S

(12) **United States Design Patent** (10) **Patent No.:** **US D1,053,487 S**
(45) **Date of Patent:** **** Dec. 3, 2024**

(54) **CLEANING CADDY**

(71) Applicant: **YouCopia Products, Inc.**, Chicago, IL (US)

(72) Inventor: **Mark Greenwood**, Evanston, IL (US)

(73) Assignee: **YouCopia Products, Inc.**, Chicago, IL (US)

(**) Term: **15 Years**

(21) Appl. No.: **29/870,432**

(22) Filed: **Jan. 26, 2023**

(51) LOC (14) Cl. **07-05**

(52) U.S. Cl.

USPC **D32/35**

(58) **Field of Classification Search**

USPC **D32/53, 55, 58**

CPC **A47K 3/281; F26B 9/10**

See application file for complete search history.

(57) **CLAIM**

The ornamental design for a cleaning caddy, as shown and described.

DESCRIPTION

FIG. 1 is a top perspective view of a cleaning caddy, showing my new design.

FIG. 2 is a front elevational view of the cleaning caddy.

FIG. 3 is a rear elevational view of the cleaning caddy.

FIG. 4 is a left side elevational view of the cleaning caddy.

FIG. 5 is a right side elevational view of the cleaning caddy.

FIG. 6 is a top plan view of the cleaning caddy; and,

FIG. 7 is a bottom plan view of the cleaning caddy.

The cleaning caddy is shown with symbolic breaks in its length and height. The appearance of any portion of the article between the break lines forms no part of the claimed design. Features shown in broken lines form no part of the claimed design.

1 Claim, 7 Drawing Sheets
